US0D1009006S

(12) **United States Design Patent** (10) Patent No.: **US D1,009,006 S**
(45) Date of Patent: ** Dec. 26, 2023

(54) **WIRELESS OMNIDIRECTIONAL
MICROPHONE**

(71) Applicants: **GUANGZHOU SHIYUAN
ELECTRONIC TECHNOLOGY
COMPANY LIMITED**, Guangzhou
(CN); **GUANGZHOU SHIRUI
ELECTRONICS CO., LTD.**,
Guangzhou (CN)

(72) Inventor: **Biliang Cheng**, Guangzhou (CN)

(73) Assignees: **GUANGZHOU SHIYUAN
ELECTRONIC TECHNOLOGY
COMPANY LIMITED**, Guangzhou
(CN); **GUANGZHOU SHIRUI
ELECTRONICS CO., LTD.**,
Guangzhou (CN)

(**) Term: **15 Years**

(21) Appl. No.: **29/806,464**

(22) Filed: **Sep. 2, 2021**

(30) **Foreign Application Priority Data**

Mar. 3, 2021 (CN) 202130116133.6

(51) **LOC (14) Cl.** **14-01**

(52) **U.S. Cl.**

USPC **D14/225**; D14/227

(58) **Field of Classification Search**

USPC D14/227, 150-151, 496, 225-226,
D14/228-229, 209.1, 240, 217, 149, 216;
D13/133, 110, 147; 381/380-381, 174

CPC H05K 5/00; H05K 5/02; H05K 5/0278;
H05K 7/00; H05K 7/20; H01R 13/60;
H04R 25/00; H04R 25/02

(57) **CLAIM**

The ornamental design for a wireless omnidirectional microphone, as shown and described.

DESCRIPTION

FIG. 1 is a front view of a wireless omnidirectional microphone showing an embodiment of the claimed design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a right front perspective view thereof; and,

FIG. 8 is a right rear perspective view thereof.

The broken lines illustrate unclaimed features of the claimed design that form no part of the claimed design.

1 Claim, 8 Drawing Sheets

US D1,009,006 S
